UNITED STATES PATENT OFFICE

2,507,789

RECIPROCATING JAW JAR WRENCH

Sellers E. Jessup, Los Angeles, Calif.

Application May 8, 1946, Serial No. 668,138

1 Claim. (Cl. 81—3.42)

1

My invention relates to improvements in reciprocable jaw jar wrench and more particularly to that type which is adapted to either remove or tighten screw top lids on jars, bottles, etc.

The primary object of the invention is to provide a hand operable wrench which is readily applicable for household or other use and by which screw covers of any ordinary diameter for use on bottles, jars and other containers can be easily and quickly unscrewed or tightened without danger of breaking the container to which it is applied or injuring the hands of the user.

Among further objects are maximum simplicity and strength of construction, ready adaptability to screw covers of various sizes and designs, increased effectiveness in use and adaptability for inexpensive manufacture.

With these and other objects in view my invention comprises the features of construction and combination of parts hereinafter described and claimed.

In the accompanying drawing forming part of this specification, Fig. 1 is a plan looking at the top side of my improved reciprocable jaw jar wrench; Fig. 2 is another plan looking at the opposite side of the structure shown in Fig. 1; Fig. 3 is an edge view of a portion of the structure shown in Figs. 1 and 2, a portion of the body being shown in longitudinal section taken on the line 3—3 of Fig. 1; Fig. 4 is a transverse section taken through the body 16 on the line 4—4 of Fig. 1, and Fig. 5 is a transverse section of the actuating lever D, taken on the line 5—5 of Fig. 1.

The character A indicates upon the drawing a main handle or actuating bar which resembles a long, flat and relatively thin piece of metal or other suitable material, having on its work end portion 11 a serrated edge 10. Arranged adjacent to the handle or power end portion 12 of member A is a movable power gripping jaw member B and in opposed relation thereto on the work end portion 11 a selectively positioned jaw member C. These jaw members B and C resemble gripping yokes having respectively inwardly facing cooperating curved serrated edge portions 13 and 14 which are adapted to tightly engage the side edge portion of the top end of a screw jaw or bottle cover of a container when the cover is applied or removed. The broken circular line 15 shown in Fig. 1, for illustration, indicates diagrammatically the marginal outline of a jar or bottle cover which is engaged by the cooperating pair of jaws B and C.

The gripping jaw member B has a body portion 16 which is passaged longitudinally at 17

2

to permit the jaw member sliding longitudinally on the handle bar. A jaw member resembling a yoke 18 is formed as an integral part of the body member. This yoke has the serrated edge 13 above described. The serrated edge portion of the yoke slants downwardly away from the adjacent side of the main handle bar so as to engage the side of a screw cover above its thread. In this manner clearance is provided for the handle bar above the cover to which the device is applied. The body portion 16 has a longitudinal guide passageway 19 on its upper side (Fig. 3), in which a helical expansion spring 20 is retained between a fixed lug or stop 21 (Fig. 3), on the handle bar and a flange or stop 22 on the rearward end portion of said passageway. A hand operating cam lever D is pivoted at 23 on the lower side of the handle bar so that the lever can be swung by its power end 24 inwardly and outwardly in relation to the handle 12. In the expanded position of jaw member B under the influence of spring 20, cam lever D is held in outstanding position as shown in Fig. 1 by the flat shoulder edge of the cam surface 25 bearing 26 against the work end of the lever D. When lever D is swung inwardly upon the handle bar by its power end the cam surface 25 forces the jaw against the tension of spring 20 with its serrated edge into tight gripping engagement with the cover of the container to which the device is applied. The longitudinal outer shoulder edge 26 of the cam lever functions as a hand grip and a stop against which the adjacent side edge of the hand grip end portion 12 of the handle bar 25 abuts to limit the inward swinging movement of the cam lever. This shoulder 26 also forms a broad gripping surface for the hand of the user.

While I have shown and described a lug or stop 21 on the handle bar and a flange or stop 22 on the housing, between which the expansion spring 20 functions, it is to be understood that the specific construction is subject to equivalent modification within the scope of the invention as set forth herein.

45 The adjustable jaw member C has a body portion 30 somewhat similar to the body portion 16 of member B, said body portion being passaged longitudinally at 31 to permit jaw member C being selectively positioned longitudinally on the work end portion of handle bar A. A forwardly extending yoke member 32 is formed as an integral part of the body member. This yoke has the serrated edge 14 above described. The serrated edge portion of the yoke slants downwardly to correspond with the portion 18 and engage the

55

upper side portion of the container cover to which the device is applied, preferably above the threaded portion thereof to also afford clearance of the handle bar above the cover. Seated in one side of the body portion 30 is an angular pawl 33 which is pivoted to swing freely upon the pin 34. The pawl lock arm 35 of this pawl is serrated at 36 to either engage the serrations 10 of the handle bar A and hold jaw member C in fixed outward position, or when disengaged by depressing a hand piece 37 on the power arm 38 to release said pawl lock arm. A helical expansion spring 39 seated in the body portion 30 and normally exerting pressure against the pawl lock arm 35 tends to hold the pawl in engagement with the bar but permits the pawl lock arm 35 to sweep over the serrations 10 when the fixed jaw member C is adjusted towards jaw member B into selected operative position against the side and above the threaded cover to be removed from or tightened upon a container.

The adjustment of the jaw member C into selected fixed position on the handle bar A increases the range of adjustment for application of the wrench to covers of different diameters ranging from small covers on bottles to large covers on jars. Due to the gripping action through leverage and hard pressure applied by the cam arm D relative to the jaw member C substantially no slippage occurs and a cover to which the device is applied and which tends to stick can be easily removed.

My improved reciprocable jaw jar wrench enables the user to apply and tighten covers on jars during canning or other operations so as to hold the jars without causing the hands of an operator to contact the hot metal of the covers. Ease of adjustment of the selectively positioned jaw member C and the shape of the jaw members enables the device to be easily applied to covers of various diameters and designs. The spring 20 returns the hand grip lever arm and clamping jaw into released position automatically ready for the clamping jaw member B to be re-applied for successive use. All of the mechanical motions afforded by the device are in the direction of operation and simple in construction. The device is serviceable for general household use and is of light weight construction. Tendency to damage the covers to which the device is applied is reduced to a minimum. All of these features are attained by my improved construction and are particularly advantageous. They cooperate so that the device can be held and operated by one hand while the jar or container to the cover of which it is applied is held securely by the other hand.

In accordance with the patent statutes, I have described the principles of operation of my invention together with the construction thereof which I now consider to represent the best embodiment thereof but I desire to have it understood that the construction shown is only illustrative and that the invention can be carried out by other means and applied to uses other than those above set forth within the spirit thereof and the scope set forth in the following claim..

I claim:

A screw cover wrench, comprising a flat handle bar having rack teeth on one longitudinal edge, an abutment jaw member movable longitudinally on said bar and in cooperative engagement with said bar and in engagement with said rack teeth, a companion jaw member having a flat transverse yoke plate formed with a heel portion at one end and an outstanding screw cover engaging serrated edge portion at the other end, said companion jaw member including a housing slidably mounted upon and embracing said handle bar with the serrated edge portion directed toward said abutment jaw member, an actuating lever pivotally secured near one end on said bar and having a substantially flat cam surface on its work end engaging against said heel and by which the companion jaw member is adapted in cooperation with said abutment jaw member to securely engage a screw cover on a jar or bottle when the free end portion of said actuating lever is swung against the handle bar, and an expansion spring within said housing and engaged longitudinally between the housing and an abutment stop on said handle bar by which the work applying jaw member and its actuating lever are returned automatically into normal biased position when said actuating lever is released.

SELLERS E. JESSUP.
